PINLESS CURTAIN STRETCHER

Robert J. Aston, Pittsburgh, Pa.

Application May 7, 1948, Serial No. 25,651

4 Claims. (Cl. 45—24)

1

The present invention appertains to improvements in stretchers for stretching curtains and various other sheets of fabrics without the employment of pins.

An important object of the present invention is to provide a stretcher of the character stated which is both portable and collapsible, the device being capable of being reduced in size to consume but a very limited space when stored away.

Another object of the invention is to provide a curtain stretcher of the type not employing pins penetrating the fabric, wherein a stand is employed, capable of being placed close to a wall or other out of the way place, thus requiring but a very limited space while in use.

A further object of the invention is to provide a pinless curtain stretcher wherein upper and lower stretcher units are employed in conjunction with a stand or other supporting means and wherein the upper unit is attached to the stand, while the other unit is suspended by the curtain and functioning as a weight fast to stretch the curtain vertically.

These and various other objects and advantages of the invention will become apparent to the reader of the following description.

In the drawings:

Figure 1 is a front elevational view of the assembly.

Figure 2 is a vertical sectional view through the assembly.

Figure 3 is a top plan view.

Figure 4 is a fragmentary enlarged vertical sectional view taken on line 4—4 of Figure 1.

Figure 5 is a fragmentary enlarged top plan view of the assembly.

Figure 6 is a fragmentary perspective view of the back bar of the upper stretcher unit.

Figure 7 is a fragmentary perspective view of the front bar of the upper stretcher unit.

Figure 8 is a perspective view of one of the curtain slide clamps.

Figure 9 is a perspective view of an intermediate bar clamp.

Figure 10 is a perspective view of a modified form of curtain clamp.

Figure 11 is a perspective view of a third form of curtain clamp.

Referring to the drawings wherein like numerals designate like parts, it can be seen that numeral 5 generally refers to a stand which may be used in conjunction with upper and lower stretcher units 6, 7.

The stand 5 is composed of a pair of parallel

base members 8, 8 from which posts 9, 9 rise and these are connected by a cross bar 10.

The posts 9, 9 are provided with pivotal extensions 11, 11, the lower ends of which are apertured to receive bolts 12 which are also disposed through openings in upper ends of the posts 9 and equipped with wing nuts 13, which when tightened, serve to hold the pivotal extensions 11, 11 in an upright position, as shown in Figures 1 and 2.

The upper ends of the pivotal extensions 11, 11 are connected or bridged by a pair of bars 14, 15, the bar 15 being a carrier bar for supporting the upper stretcher unit 6.

The upper stretcher unit 6 is composed of a back bar 16 formed with a slot 17 extending inwardly from each end thereof and terminating inwardly of the intermediate portion of the bar.

L-shaped plates 18 are secured to the end portions of the back bar 16 in a position so that one flange thereof will project forwardly, as shown in Figure 6. Adjacent each end of the back bar 16 an L-shaped hook 19 is secured to the upper edge thereof and these are engaged over the hanger bar 15, as shown in Figure 2 when the upper unit 6 is being supported.

In conjunction with the back bar 16, the upper unit 6 also employs a front bar 20 having substantially wide slots 21 at the end portions thereof. U-shaped members 22 are secured to the ends of the front bar 20 with their bight portions slightly spaced from the adjacent ends of the bar 20 to afford passageways 23 for the snug reception of the flanges *a* of the L-shaped plates 18 carried by the back bar 16. Set screws 24 are feedable through the bight portions of the U-shaped members 22 to bite against the flanges *a* to hold the bars 16, 20 in proper relation.

To hold the intermediate portions of the bars 16, 20 substantially together, a clamp such as is generally referred to by numeral 25 in Figure 9 may be employed, this clamp 25 being made up of a U-shaped element 26 having a long leg *b* and a short leg *c*. A clamp screw 27 is feedable through the leg *c* which straddles the bar 20 and this screw 27 carrying a pressure foot 28 serves to clamp the bars 16, 20 against the back leg *b* and against whatever fabric is interposed between the bars.

For stretching and holding the curtain or the fabric stretched, a pair of clamps generally referred to by numeral 29 are employed. Each clamp being composed of a U-shaped member 30 having back and front legs 31, 32 respectively, with a clamp screw 33 feedable through the leg

32 to clamp a curtain or the like X (see Figure 1) against the leg 31.

The back side of the leg 31 carries a V-shaped spring element 34 which while slidable in the slot 17, has sufficient frictional boss as to hold the curtain stretched when the clamps 29 are moved in a direction toward the ends of the corresponding unit 6 or 7. Obviously the clamps 29 can be removed by simply pulling the same outwardly from the back bar 16 and it is apparent that these clamps can be readily reached and shifted by reason of the large slots 21 in the front bar 20.

In place of the clamp shown in Figure 8 and denoted by reference character 29, a clamp such as shown in Figure 10 and denoted by numeral 35 may be employed, this clamp consisting of a spring clip 36 having flared end portions 37, 37 to permit the free entrance of fabric therebetween and between the spring jaws. One jaw of the spring clip 36 carries a V-shaped spring detent 38 which is slidable in the corresponding slots 17 in the same manner as the spring element 34 of the clamp 29.

A third form of clamp is shown in Figure 11 and denoted by numeral 39, this clamp consisting of a U-shaped member 40 including legs 41, 42, 41 having a clamp screw 43 feedable therethrough, while the leg 42 has a strip of spring metal disposed over the same and compressed behind the same to extend outwardly to provide slightly diverged spring fins 44, 44, which can be compressed and inserted in the slot 17 (see Figure 6) to function in the same manner as the spring members 34, 38 of the clamps 29, 35.

If the lower unit 7 is to always function as the weight unit of the assembly, it need not be provided with the hooks 19. However, to make the units interchangeable, both units may employ the hooks 19 for disposition over the hanger bar 16 of the stand 5.

In the use and operation of the apparatus, the stand in folded position is first taken out of storage and the pivotal extensions 11, 11 raised and held in that position by the clamping action of the bolts 12 and nuts 13.

The units 6, 7 are now attached to the ends of the curtain and the clamps 29 (or any form of clamp employed) moved outwardly along the slot 7 until the curtain is properly stretched. The bars 16, 20 are now pressed together, the set screws 24 tightened and the clamps 25 (intermediate) tightened and placed, especially in the instance where wide curtains are being stretched.

The unit 6 having the hooks 19 is now held up and the hooks 19 engaged over the hanger bar 15 of the stand. The curtain is now allowed to depend from the upper portion of the stand and the lower unit 7 will act as a weight in stretching the curtain downwardly, while the unit 6, 7 serves to stretch the curtain horizontally.

While the foregoing description sets forth the invention in specific terms, it is to be understood that numerous changes in the shape, size and materials may be resorted to without departing from the spirit and scope of the invention as claimed hereinafter.

Having described the invention what is claimed as new is:

1. A fabric stretcher comprising an upper stretcher unit and a lower stretcher unit, means for supporting the upper unit, the lower unit being supported by the fabric and acting as a weight to stretch the fabric downwardly, each of said units including an outer member and an inner member, said inner members each being formed with a slot in each end thereof, a fabric-engaging clamp associated with each of the slots, said clamps each having affixed thereto a frictional spring slidably and adjustably disposed in an adjacent slot, and said spring being in the form of a pair of diverged spring elements adapted to be compressed and inserted into a selected portion of the adjacent slot.

2. A fabric stretcher comprising an upper stretcher unit and a lower stretcher unit, means for supporting the upper unit, the lower unit being supported by the fabric and acting as a weight to stretch the fabric downwardly, each of said units including an outer member and an inner member, said inner members each being formed with a slot in each end thereof, a fabric-engaging clamp associated with each of the slots, said clamps each having affixed thereto a frictional spring slidably and adjustably disposed in an adjacent slot, and said spring being in the form of a V with its bight portion engageable in a selected portion of the adjacent slot.

3. A device as defined by claim 1 wherein means is provided in the outer members for manual access to the clamps.

4. A device as defined by claim 2 wherein means is provided in the outer members for manual access to the clamps.

ROBERT J. ASTON.
